UNITED STATES PATENT OFFICE

151,887

DESIGN FOR A SLIP

Karl Kaplan, New York, N. Y.

Application April 1, 1947, Serial No. 138,096

Term of patent 14 years

(Cl. D3—26)

To all whom it may concern:

Be it known that I, Karl Kaplan, a citizen of the United States and resident of New York city, in the county of New York and State of New York, have invented a new, original, and ornamental Design for a Slip, of which the following is a specification, reference being had to the accompanying drawing, forming a part thereof and of which Figure 1 is a front view in flat position of a slip showing my new design; and Fig. 2 is a side view of the slip as worn.

The back of the slip is of conventional configuration.

The essential feature of the design resides in the configuration of the bust portion as shown.

I claim:

The ornamental design for a slip, substantially as shown and described.

KARL KAPLAN.
